UNITED STATES PATENT OFFICE

2,528,495

REPEATING AIR GUN

Eddie E. Carter, Rochester, N. Y.

Application February 8, 1946, Serial No. 646,368

4 Claims. (Cl. 124—15)

1
This invention relates to guns, and more particularly to air guns operated by springs, and adapted to discharge either one or a plurality of pellets successively from the device, in response to each single pull of the trigger.

A further object of the invention is to provide a magazine air rifle so constructed that it will not be necessary to supply a store of compressed air for operation of the rifle.

It is still a further object of the invention to provide an air rifle powered from a coil spring which may be tensioned by a single operation of a conveniently located lever. Release of the spring in response to trigger action causes ejection of a shot, for each trigger action, until a total of five shots have been ejected, or as an alternative operation the trigger may be maintained in actuated position, whereupon the rifle will continue to eject shot until a total of five have been ejected, without further action on the part of the operator.

It is a still further object of the invention to provide an air rifle in which loading of the shot is automatic and takes place in response to spring urging, rather than by gravity, to assure positive loading action in all attitudes of the rifle.

It is still a further object of this invention to provide an air rifle of the character above described which shall be so constructed and arranged as to lend itself to economical manufacture, and of such simplified construction as to enable ready assembly and disassembly for repair and replacement of parts, as required.

Still further objects of this invention will become evident upon study of the following specification when taken in connection with the accompanying drawings, wherein like numerals of reference are applied to the same parts throughout the several figures, and wherein:

Figure 1 is a side elevational view of the rifle embodying my invention, illustrating the appearance thereof when completely assembled;

Figure 2 is a vertical section taken along a longitudinal axis of the rifle and illustrating various of the operating mechanisms of the gun in assembled relation;

Figure 3 is a section taken on the line 3—3 of Figure 2;

Figure 4 is a section taken on the line 4—4 of Figure 2;

Figure 5 is a sectional view taken along a longitudinal axis of the barrel of the rifle, and illustrating particularly the shot loading and feeding mechanism;

Figure 6 is a section taken on the line 6—6 of Figure 5.

2
Figure 7 is a side elevational view of a detail associated with the loading mechanism;

Figure 8 is a side elevational view of a magazine associated with the loading and feeding mechanism;

Figure 9 is a plunger device, illustrated in side elevation, for ejecting shot from the rifle;

Figure 10 is a view in perspective of a mechanical detail associated with the invention; and

Figures 11 to 14 inclusive are perspective views of certain levers associated in the firing mechanism of the rifle, and illustrated in assembled relation, in Figure 2 of the drawings.

Referring now to the drawings in detail 1 represents a gun barrel, having a forward sight 2 secured thereto in customary position. The stock of the rifle is indicated by the numeral 3, and may be constructed of wood or of metal, if desired. Secured to the stock 3 and intermediate 20 between the stock 3 and the barrel 1 is located the shot ejecting mechanism, denoted generally by 4 and located within the metal housing 5. Lever 6 serves to cock the rifle or to condition it for firing upon pulling of the trigger 7, the lever 6 being suitably cut away adjacent the trigger 7 to form a trigger guard therefor.

Referring particularly to Figures 5 to 8 inclusive which illustrate the shot loading and feeding mechanism and the structure of the barrel of the rifle, it will be evident that 10 represents the outer barrel of the rifle in the shape of a long hollow thin walled cylinder, and that, located axially of the cylinder 10 and spaced therefrom by a pair of annular members 11 and 12 is a further long hollow thin walled cylinder 13 which corresponds to the bore of the rifle and provides a passage for ejected shot.

While the annular member 11 performs no function except its spacing function, the member 12 provides a relatively complex structure to assist in the feeding of shot to the bore 13 and retaining of each shot in the bore in position to be ejected upon suitable violent actuation. The member 12 comprises in the space between the inner wall of the barrel 10 and the outer wall of the bore 13, and located under the bore, in the normal horizontal attitude of the rifle, a chamber 14 in the form of a passageway for shot 15, said chamber turning upwardly at its rearward outlet to communicate with the bore 13, said bore 13 being provided with a small aperture 16 for this purpose. A plunger 17 rides for a portion of its length within the forward end of a tube 22 constituting a magazine for pellets, and at a point adjacent its forward termination rides in a bearing provided in a lug 18 downwardly de-

pending from the bore 13. Secured to the plunger 17 at a point intermediate its ends, and extending downwardly through a slot 19 in the outer barrel 10 is a lug 20. Surrounding the plunger 17 and tending to separate the lugs 18 and 20 is a compression spring 21, which exerts a constant pressure on the pellets or shot 15 tending to force said shot to the right in the magazine 22 and the chamber 14 and through aperture 16 into the bore 13.

The channel 24, illustrated in perspective view in Figure 7, consists of a channel having a flat base 25 and two upstanding sides 26. One side 26 extends beyond the end of the base 25 in an ear 27 having a pivoted connection to a strap 28 surrounding the bore 13. At the end of the channel 24 opposite to the ear 27 is a catch 29. The channel 24, by virtue of the pivotal connection 28 serves as a lock which may be opened, as shown in dotted outline in Figure 5, for insertion of a magazine 22 loaded with shot, and thereafter closed to the position illustrated in full lines in Figure 5, whereby the said channel 24 will retain the magazine 22 in position for shot to be fed to the firing chamber under the lever 30. To permit the removal and replacement of the magazine 22 the plunger 17 is retracted by pulling forward on the lug 20. After insertion of the magazine 22 and closing of the lock or channel 24 the lug 20 is released, whereupon spring 21 forces the plunger to the right, in Figure 5, and partially within the magazine 22 and the channel or lock 24 in proper position. Catch 29 may be pulled downwardly to open the channel or lock 24.

After delivery to the bore 13 of each pellet by the pressure of succeeding pellets, which are themselves pressed by the spring 21 acting through the plunger 17, the said pellet within the bore 13 is retained against forward motion by means of the lever 30 which is spring pressed at one end by a spring 31, and which pivots about a pin 32, said spring and pivot being located in a chamber 33 formed in the annular member 12. The spring 31 is sufficiently powerful to overcome the force exerted by the spring 21 and permits only a single pellet to emerge into the bore 13 at any one time and retains said pellet in position to be ejected from the bore by a normal firing operation, regardless of the attitude of the gun intermediate successive firings thereof.

The pellets are ejected from the bore 13 by a violent actuation of the plunger 40 which rides within the bore 13 and transmits its motion to the pellet and also by the air pressure generated by rapid movement of the piston 41 within the chamber 41' said pressure being communicated to the pellet continually during its passage down the bore 13. Upon withdrawal of plunger 40 air is drawn into the chamber 41' by the retraction of piston 41 and after withdrawal of plunger 40 rearwardly to a sufficient extent to uncover the aperture 16 a succeeding pellet feeds into the bore 13 and is secured by the lever 30 in position for a succeeding firing operation of the plunger 40.

The plunger 40 is impelled violently forward to cause expulsion or firing of a pellet 15 by the action of a latch 52 pivotally secured to the plunger 40 by means of a pin 45 and arranged and adapted to be struck at the tail end 46 thereof by a series of hammers 43 arranged about the periphery of a cylinder 44. The plunger 40 at its rearward end is provided with and secured to a laterally extending member 47, said member 47 comprising a pair of laterally extending ears 48 which ride in slots 49, 50, the slot 49 being formed in a wall

5 of the housing 5 and the slot 50 being provided in a plate 51 which may be secured to the housing 5 by means of screws set in a plurality of apertures 52 in the plate 51. The plunger 40 is restrained into its rearwardmost position by the coil spring 53, which acts to return the plunger 40 to unactuated position ready for another operation after each pellet ejecting operation of the said plunger.

10 The latch 42 is spring pressed toward the drum or casing 44 by means of a bent spring 54 acting on lever 55 which is pivotally secured to the plate 51 by means of pin 56, the spring 54 extending from a pin 86 secured to the plate 5, in a loop over the upper surface of the lever 55. Pin 87 acts as a stop to prevent undue pivotal motion of the lever 55.

15 The internal gear sector 60 is secured to or made integral with the lever 6, and an operation of the said lever away from and to the stock 3 of the rifle causes a reciprocating angular motion of the sector 60 about the stud 61 as a pivot, the said stud being formed in the plate 51, or secured thereto.

20 Movement of the gear sector 60 causes rotation of the gear 62, which is rotatable on the shaft 63, the latter finding support in the walls 64, 65 of the housing 5. One end of the shaft 63 (see Figure 3) is drilled and tapped for reception of a screw 66, the other end of the said shaft 63 being provided with a shoulder 67, which is located externally of the wall 64 as is also the head of screw 66 with respect to the wall 65.

25 Rotatably mounted on shaft 63 is the cylindrical casing 44 about the periphery of which are located the ratchet-like hammers 43, and within the said casing 44 is located a helical spring 67, of extremely powerful construction secured at its internal extremity to the shaft 63 by means of a screw or rivet 68 and at its outer end to the casing 44 by means of a pin 69 extending between the walls of the casing 44. The gear 62 is secured to the casing 44 by means of a spring pressed pawl 70, for actuation of the casing 44 by the gear 62 in one direction of actuation of the gear only, that is on the actuating stroke of the lever 6, the lever 6 and the gear 44 being free to move back to unactuated position without causing any movement of the drum or casing 44. The hammers 30 43 are shaped after the manner of ratchet teeth to enable them to pass in one direction with respect to latch 42 but to engage said latch in the opposite direction of travel. Actuation of the casing or drum 44 by the gear 62 serves to tighten 45 the spring 67, said spring providing the force which is ultimately applied to the pellets or shot 50 55 15 for expelling same forcibly from the gun.

55 With the spring 67 under tension as a result of actuation of the lever 6, the drum or casing 44 is nevertheless restrained against movement by the latch member 71 having a latching shoulder 91 and pivoted on a pin 92. The said latch member is pressed against the peripheral surface of the drum 44 by means of a link 72, secured pivotally 60 to both the latch 71 and a further latch 73, which is spring pressed by the spring 74 coiled about the pivot pin 75 upon which latch 73 is pivotally mounted, and having two protruding ends 76 and 77, one end 76 pressing against the pin 78 secured 65 to the housing 5 and the other end 77 pressing the link 72. The latch 73 is secured by a hook 80 formed in a draw bar 81 which is pivotally mounted on a pin 82 secured to the trigger member 83. The draw bar 81 is spring urged into hooking 70 75 engagement with the latch 73 by means of a

spring 84 which coils about the pin 82 and is secured at one end behind a pin 85 on which the trigger member pivots and at the other end behind a pin 86" on the draw bar 81.

After the rifle has been cocked by operation of the lever 6 to rotate the drum or casing 44 whereby to tension the spring 67, the rifle is ready for firing.

If the trigger is now pulled, against the force of the compression spring 88, draw bar 81 is pulled to the right, in Figure 2, hook 80 exerting force on latch 73 which retracts latch 71 from behind the hammer 43 and permits the coiled spring to rotate the drum or casing 44. That one of the hammers or teeth 43 which had been restrained by the latch 71 rotates violently through an angle of about 60° and then impinges on the tail 46 of latch 42 which is subjected to the entire momentum of the casing or drum 44 and causes a violent leftward movement of plunger 40, causing ejection of a pellet 15 in a manner already explained. If the trigger should be retained in actuated position, the latch 27 will be retained out of the path of the teeth or hammers 43 and the above action will take place successively until the tension in the spring has become exhausted.

If on the other hand the trigger is released immediately upon being pulled, the release of the trigger will permit the latch 71 to return to contact with the periphery of the drum or casing 44, and enables said latch 71 to interrupt the action of the entire mechanism after only a single shot has been fired.

Figures 10 to 14 inclusive illustrate various parts of the device, certain features of which are described below.

Referring to Figure 10 of the drawings, apertures 56', 85', and 87' in the plate 51 are provided for insertion of the pins 56, 86" and 87 respectively, and which extend rearwardly of the plate 51 as seen in Figure 10.

Referring to Figure 14 of the drawings, which illustrates the trigger 7, 82' is a hole in which may be secured pin 82 and 85' a hole for pivotally mounting on the pin 85 about which the entire trigger structure pivots. Projection 90 is encompassed by one end of spring 88 which provides a compressive force against which the trigger must be pulled, the other end of said spring 88 nesting in a small recess 89 in the stock 3 of the rifle.

In Figure 12 the hole 92' pivots on a pin 92 (see Figure 2 of the drawing) and in Figure 13 the hole 82" pivots on a pin 82 (see Figure 2) secured in the hole 82' of trigger member 7.

It was mentioned supra that five pellets could be ejected from the rifle above described and illustrated in the accompanying drawings, upon one actuation of the trigger of the rifle. It will, of course, be obvious that by increasing or decreasing the number of hammers 43 on the drum 44, that the number of shots could be increased or decreased, and further that with the structure exactly as herein described and illustrated, if the lever 6 were actuated a plurality of times before one firing operation, resulting in extreme tension of the spring 67, that many more than five pellets could be ejected from the rifle before a recocking operation would be again necessary. The pellets feeding mechanism is quite independent of the ejecting mechanism and, so long as sufficient pellets are available in the magazine, will continue to feed these pellets to the bore of the rifle into position for ejection.

What I claim is:

1. In a gun having a barrel provided with a bore through which one of a plurality of pellets may be projected at a time from a position in the rear of said bore, a plunger comprising a rod extending forwardly through the rear end of said bore, return-spring means normally retracting said plunger to a rearward starting position, said plunger rod having a pivoted trailing tongue, plunger actuating means for driving said plunger forwardly from its starting position against the resistance of said return-spring means so as to cause the forward end of said rod to move forwardly in said bore and project the pellet forwardly through said bore, said plunger actuating means comprising a rotary drum having a plurality of circumferentially spaced hammers on its periphery positioned in the path of the trailing end of said tongue, said drum normally occupying a position in which the one of said plurality of hammers which is adjacent to said tongue is disengaged from said tongue, drive-spring means associated with said drum for rotating said drum in firing direction from said position so as to cause said adjacent one of said hammers to strike the trailing end of said tongue and thereby drive said plunger forwardly, cocking means comprising means for rotating said drum in the opposite direction so as to tension said drive-spring means, spring pressed pawl means normally engaging peripheral portions on said drum to retain said drum in said normal position and prevent said drum from rotating in said firing direction after operation of said cocking means to tension said drive-spring means, and spring positioned trigger means operatively connected to said pawl means, said trigger means being arranged to be moved out of its normal position to retract said pawl means and thereby permit rotation of said drum in the firing direction for a distance between two adjacent hammers so as to fire one pellet through said bore and said trigger being arranged to be released to its normal position so as to reengage said pawl means with said drum and thereby preclude further rotation of said drum in the firing direction, said trigger means being adapted to be moved and retained out of its normal position and permit said drum to rotate in the firing direction so as to engage successive ones of said hammers with the trailing end of said tongue so as to produce burst-firing of a plurality of successive pellets through the barrel bore.
2. In a gun having a barrel including a bore through which pellets are adapted to be projected, pellet magazine means having communication with said bore for feeding pellets one at a time into said bore, a spring retracted plunger rod arranged to be operated forwardly in said bore from a starting position to project a pellet therefrom, said rod having a striking portion, and actuating means for operating said rod forwardly from its retracted starting position, said actuating means comprising a rotary drum having at least two circumferentially spaced peripheral hammers, said hammers being engageable successively with said striking portion of said plunger rod as said drum is rotated in one direction whereby said plunger rod is operated forwardly by engagement of one of said hammers with said striking portion to project a pellet and permitted to return to starting position before the succeeding hammer can engage said striking portion, drive-spring means operatively connected to said drum for rotating said drum in said one direction,

cocking means for rotating said drum in the opposite direction for tensioning said drive-spring means, spring pressed pawl means arranged to be engaged by one of said hammers whereby said drum is retained against being rotated in said one direction by said drive-spring means, and trigger means comprising a spring positioned trigger and means operatively connecting said trigger to said pawl means whereby operation of said trigger in one direction releases said pawl means from the hammer engaged thereby and permits said drum to be rotated in said one direction by said drive-spring means and engage a succeeding hammer with the striking portion of the plunger rod.

3. In a gun having a barrel provided with a bore through which a pellet is adapted to be projected, a spring retracted plunger rod extending forwardly in said bore, a trailing tongue pivoted on said rod, and actuating means for driving said rod forwardly from its retracted starting position to project a pellet present in said bore, said actuating means comprising a rotary drum having a plurality of peripheral hammers positioned in the path of the trailing end of said tongue, drive-spring means associated with said drum for rotating the drum in one direction to engage one of the hammers with the trailing end of the said tongue with sufficient force to drive the plunger forwardly in the barrel bore, means for tensioning said drive spring means, spring pressed pawl means positioned in the path of the hammers and engageable with one of the hammers to hold the drum against rotation in the said one direction by said drive-spring means, said hammers being sufficiently circumferentially spaced around said drum to enable one of said hammers to strike and pass the trailing end of said tongue before the next hammer comes into engagement with said pawl means and permit said plunger rod to resume its retracted starting position, and trigger means comprising a spring positioned trigger operatively connected to said pawl means, said trigger being arranged to be moved from a starting position to an operated position so as to withdraw said pawl means from retaining engagement with said next hammer and permit said drum to rotate in said one direction and engage said next hammer with the trailing end of said tongue.

4. In a gun having a barrel provided with a bore through which a pellet is adapted to be projected, a spring retracted plunger rod extending forwardly in said bore, a trailing tongue pivoted on said rod, and actuating means for driving said rod forwardly from its retracted starting position to project a pellet present in said bore, said actuating means comprising a rotary drum having a plurality of peripheral hammers positioned in the path of the trailing end of said tongue, drive-spring means associated with said drum for rotating the drum in one di-

rection to engage one of the hammers with the trailing end of the said tongue with sufficient force to drive the plunger forwardly in the barrel bore, means for tensioning said drive spring means, spring pressed pawl means positioned in the path of the hammers and engageable with one of the hammers to hold the drum against rotation in the said one direction by said drive-spring means, said hammers being sufficiently circumferentially spaced around said drum to enable one of said hammers to strike and pass the trailing end of said tongue before the next hammer comes into engagement with said pawl means and permit said plunger rod to resume its retracted starting position, and trigger means comprising a spring positioned trigger operatively connected to said pawl means, said trigger being arranged to be moved from a starting position to an operated position so as to withdraw said pawl means from retaining engagement with said next hammer and permit said drum to rotate in said one direction and engage said next hammer with the trailing end of said tongue, said trigger being releasable from its operated position to its starting position after the said one hammer has engaged said tongue and produced projection of a pellet and before said next hammer has reached said tongue whereby said pawl means will engage said next hammer and retain said drum against further rotation in said one direction, and said trigger being arranged to be held in its operated position so as to maintain said pawl means out of engagement with successive ones of said hammers whereby said drum can continue to rotate in said one direction to engage successive ones of said hammers with the trailing end of said tongue to provide repeated projection of pellets through said barrel bore by said plunger rod.
